It is certified that error appears in the above-identified patent and that said Letters Patent is hereby corrected as shown below:

This certificate supersedes the Certificate of Correction issued on November 25, 2014. The certificate which issued on November 25, 2014 is vacated because the drawings (filed on March 28, 2014) which appear on the certificate were not approved by the examiner. The Certificate of Correction which issued on November 25, 2014 was published in error and should not have been issued for this patent.

Title page should be deleted and substitute therefor the attached title page.

In the Drawings:

Delete Figs. 1-7 and substitute therefor Figs. 1-7 as shown on the attached pages.
